US00D917926S

(12) **United States Design Patent** (10) **Patent No.:** **US D917,926 S**
(45) **Date of Patent:** **** May 4, 2021**

(54) **PILLOW**

(71) Applicant: **Purple Innovation, LLC**, Alpine, UT (US)

(72) Inventors: **Tony M. Pearce**, Alpine, UT (US); **Russell Whatcott**, Eagle Mountain, UT (US)

(73) Assignee: **Purple Innovation, LLC**, Lehi, UT (US)

(**) Term: **15 Years**

(21) Appl. No.: **29/676,858**

(22) Filed: **Jan. 15, 2019**

Related U.S. Application Data

(63) Continuation-in-part of application No. 15/333,486, filed on Oct. 25, 2016.

(51) **LOC (13) Cl.** **06-09**

(52) **U.S. Cl.**

USPC **D6/601**

(57) **CLAIM**

The ornamental design for a pillow, as shown and described.

DESCRIPTION

FIG. 1 is a perspective view of a design for a pillow; FIG. 2 is a first side view of a length of the pillow shown in FIG. 1;

FIG. 3 is a second side view of a width of the pillow shown in FIG. 1;

FIG. 4 is a top view of the pillow shown in FIG. 1;

FIG. 5 is a bottom view of the pillow shown in FIG. 1; and, FIG. 6 is a perspective bottom view of the pillow shown in FIG. 1.

The broken lines illustrate features of the pillow that form no part of the claimed design.

1 Claim, 5 Drawing Sheets
